UNITED STATES PATENT OFFICE.

JACOB HENDRICKSON, OF BUTTE, MONTANA, ASSIGNOR OF ONE-HALF TO ISAK W. JOHNSON, OF ROSSLAND, BRITISH COLUMBIA, CANADA.

PERMUTATION-LOCK FOR SUITCASES, GRIPS, &c.

1,172,454.

Specification of Letters Patent.

Patented Feb. 22, 1916.

Application filed April 14, 1915. Serial No. 21,397.

To all whom it may concern:

Be it known that I, JACOB HENDRICKSON, a citizen of the United States, residing at Butte, in the county of Silverbow and State of Montana, have invented a new and useful Permutation-Lock for Suitcases, Grips, &c., of which the following is a specification.

The present invention appertains to permutation locks, and aims to provide a novel and improved permutation lock adapted particularly for use in suit cases, grips, and kindred devices embodying two frames or members arranged to swing or move to and from each other, the lock being adapted for locking the frames or members together whereby they cannot be separated or opened unless the combination is known.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:—

Figure 1 is a plan view of the two frames or members swung apart or open, portions being broken away, and the inner parts of the lock being illustrated. Fig. 2 is a side elevation of the device, portions being broken away. Fig. 3 is a cross section taken on the line 3—3 of Fig. 2. Fig. 4 is a longitudinal section taken on the line 4—4 of Fig. 2.

In the drawings, the numerals 1 and 2 designate two frames or members which are hinged or pivoted together, as at 3, whereby they may swing or move to and from each other. Frame members of this character are commonly used in suit cases, grips, and other containers, for opening and closing the same, and it is the object of the invention to provide a permutation lock for locking the frames or sections 1 and 2 together in order that the suit case, grip or other container may be effectively held in closed position. The members 1 and 2 are therefore taken to represent broadly the frame members of a suit case, grip, or other device or container, since the present lock may be applied to various articles. The sections or frames 1 and 2

of a suit case, grip or the like, are usually provided with flanges or portions 4 to overlap one another when the frames or sections are swung together for closing the container. The flanges 4 serve to conceal the working parts of the lock when the frames 1 and 2 are swung together.

In carrying out the invention, spindles 5 and 6 are journaled through the free portions of the frame members 1 and 2 so that they aline when the frame members are swung together, and the outer ends of the spindles 5 and 6 are provided with the respective knobs 7 and 8. Dials 9 and 10 are mounted loosely upon the respective spindles 5 and 6 at the inner sides of the respective frame members 1 and 2, and the outer sides or faces of the dials 9 and 10 are provided with suitable graduations, characters or indicia which are exposed one at a time through the apertures or openings 11 provided in the members 1 and 2. Tumbler disks 12 and 13 are secured rigidly to the inner ends of the spindles 5 and 6, respectively, the dials 9 and 10 being rotatable upon the spindles between the tumbler disks and frame members, when the dials are released, but the dials are normally constrained to rotate with the tumbler disks by means of screws or other securing elements 13^a engaged through the tumbler disks and taking into the dials. Each of the dials has an annular series of threaded bores for receiving the respective screws 13^a, whereby when the screws are loosened or removed, the dials may be rotated upon the spindles to set the dials at different positions with respect to the tumbler disks, when it is desired to change the combination. After the dials have been adjusted, the screws 13^a are reapplied to secure the dials to the tumbler disks.

The peripheries of the dial 9 and tumbler disk 12 are beveled to provide an annular groove 14 between said dial and disk, and the peripheries of the dial 10 and disks 13 are similarly beveled to provide an annular groove 15 between the last mentioned dial and disk. The disk 12 has a notch 18 in its periphery extending from the inner side of the disk 12 to the groove 14, and the periphery in the disk 13 is provided with a similar notch 19 extending from the inner side of the disk 13 to the groove 15. The inner sides of the disks 12 and 13 are provided

with the respective recesses or depressions 16 and 17, and the disk 12 is provided with a radial notch or slot 20 extending from the recess 16 to its periphery, while the disk 13 is provided with a radial slot or notch 21 extending from the recess 17 to the periphery of the disk 13.

10 A finger or element 22 is secured to the frame member 1 and projects beyond the disk 12, and has an angularly extending hook 23 at its free end to be engaged by the opposite tumbler disk 13. A similar finger or element 24 is secured to the frame member 2 and projects beyond the respective tumbler disk 13, and has an angularly extending hook 25 at its free end to be engaged by the opposite tumbler disk 12. The hooks 23 and 25 are adapted to be passed through the notches 19 and 18, respectively, as will 15 hereinafter appear to be received by the respective grooves 15 and 14.

20 A sliding or reciprocatory lock bolt 26 is slidable through suitable bearings or guides 27 carried by the frame member 2 upon the inner side thereof, and a pin 28 engaged to the lock bolt 26 works within a longitudinal slot 29 provided in the frame member 2, a suitable finger piece 30 being carried by the outer end of the pin 28 and sliding upon the 25 outer side of the frame member 2 for conveniently manipulating the lock bolt from the outside. The frame member 1 has an apertured ear or portion 31 projecting from its inner side and through which the bolt 26 is adapted to be projected when the bolt is moved into engagement with the tumbler disks. The active end of the bolt 26 is provided with a head 32 adapted to pass 30 through the notches or slots 20 and 21 of the tumbler disks when the tumbler disks are set properly, so that the head 32 can be locked between the tumbler disks.

35 In operation, to lock the frame members 1 and 2 together, the tumbler disks 12 and 13 are set properly by bringing the proper numerals or indicia of the dials within the openings 11, so that when the frame members 1 and 2 are swung together, the hooks or lugs 23 and 25 may pass through the respective notches 19 and 18 of the opposite tumbler disks. The tumbler disks are then 40 rotated to move the notches or slots 20 and 21 into alinement and into position to receive the headed end of the bolt 26, and the bolt is then slid so that its head 22 passes through the notches 20 and 21 into the recesses 16 and 17 of the tumbler disks. The tumbler disks are then again rotated 45 which will cause the head 32 to be locked between the tumbler disks and within the rims or recesses thereof. When the bolt 26 is slid toward the tumbler disks, it is passed through the apertured ear 31 of the opposite frame member 1, whereby the bolt 26 will 50 hold the frame members together, and fur-

thermore, it is to be noted that the hooks 23 and 25 engaging behind the opposite tumbler disks, will also serve to hold the frame members in folded or closed position. In this manner, three distinct means are 55 provided for holding the frame members together, and it requires a predetermined operation of the parts for releasing the frame members, it being necessary to adjust or set each tumbler disk twice.

60 To release or unlock the frame members 1 and 2, the tumbler disks are first rotated to bring the notches 20 and 21 into alinement and to such a position that the head 32 of the bolt 26 may be retracted from between 65 the tumbler disks through the said notches and out of the apertured ear 31 of the frame member 1. This requires that each tumbler disk be set properly before the bolt 26 can be retracted. Then, each of the tumbler 70 disks must again be rotated to another position so that the notches 18 and 19 of the respective tumbler disks align with the hooks or lugs 25 and 26, respectively, of the keeper fingers 24 and 22. Then, the frame members may be swung apart since the hooks or lugs 23 and 25 may pass through the respective notches 19 and 18.

75 The tumbler disks may be readily rotated from the outside by turning the knobs 7 and 8, and the dials 9 and 10 which have their numbers or graduations exposed in succession through the openings 11, enable the tumbler disks to be set properly. The combination may be changed by readjusting the 80 dials 9 and 10 with respect to the tumbler disks, when the frame members 1 and 2 are separated.

85 The present permutation lock is comparatively simple, compact and inexpensive in 90 construction, may be readily applied to the frame members of suit cases, grips, and other containers and devices for effectively holding the frame members together.

95 Having thus described the invention, what is claimed as new is:

100 1. In a device of the character described, the combination with a pair of members movable to and from each other, of a manually operable tumbler carried by one member, means carried by the other member and engageable with the tumbler to be held thereby until the tumbler is set at a predetermined position, a lock bolt carried by one member and arranged to be moved into engagement with the tumbler to be held thereby until the tumbler is moved to another predetermined position, and means carried by the other member for the engagement therethrough of the bolt when the bolt is moved into engagement with the tumbler.

105 2. In a device of the character described, the combination with a pair of members movable to and from each other, of a manually operable tumbler carried by each of

the said members, and elements carried by the said members and engageable with the opposite tumblers when the members are moved together and whereby each of the 5 tumblers must be set to a predetermined position to enable the members to be separated.

3. In a device of the character described, the combination with a pair of members movable to and from each other, of a manually operable tumbler carried by each member, a lock bolt carried by one member, an element carried by the other member through which the lock bolt is movable when the lock bolt is engaged to the tumblers, the 10 bolt and tumblers having interengageable means whereby each of the tumblers must be set at a predetermined position to enable the bolt to be released.

4. In a device of the character described, 20 the combination with a pair of members movable to and from each other, of a manually operable tumbler carried by each member, a lock bolt carried by one member, means carried by the other member for the engagement therethrough of the bolt when the bolt is moved into engagement with the tumblers, and means carried by the said members and engageable with the opposite tumblers, whereby the tumblers must each be 25 set at two predetermined positions for successively releasing the bolt and last mentioned means.

5. In a device of the character described, the combination with a pair of members 35 movable to and from each other, of a spindle journaled through each member, a tumbler disk secured to the inner end of each spindle, each tumbler disk having a notch in its periphery, and elements secured to the said 40 members and having portions to move through the said notches and engage behind the opposite tumbler disks.

6. In a device of the character described, the combination with a pair of members 45 movable to and from each other, of a spindle journaled through each member, a tumbler disk secured to the inner end of each spindle, the inner side of each disk having a recess, each disk having a notch extending from the 50 said recess to its periphery, a lock bolt slidably carried by one member, and an apertured element carried by the other member through which the bolt is arranged to be passed when the bolt is projected into engagement with the tumbler disks, the bolt 55 having a headed end to move through the said notches when the tumbler disks are set properly and to be locked within the said recesses.

60 7. In a device of the character described, the combination with a pair of members movable to and from each other, of a spindle journaled through each member, a tumbler disk secured to the inner end of each 65 spindle, the inner side of each disk having a

recess, each disk having a notch in its periphery and the notch extending from the said recess to the periphery of the disk, an element secured to each member and having a portion to move through the first mentioned notch of the opposite disk when the members are moved together, a lock bolt 70 slidably carried by one member and an apertured portion carried by the other member through which the lock bolt is engageable when the bolt is projected into engagement with the tumbler disks, the bolt having a head at one end to move through the second mentioned notch of each disk when the disk is set properly, said head being adapted to 80 be locked between said recesses.

8. In a device of the character described, the combination with a pair of members movable to and from each other, of a spindle 85 journaled through one member, a tumbler disk secured to the inner end of the spindle, an element carried by the other member and engageable with the tumbler disk whereby the tumbler disk must be set at a predetermined position to enable said 90 element to be released, a lock bolt slidably carried by one member and an apertured element carried by the other member through which the bolt is movable when the bolt is projected into engagement with the tumbler 95 disk, the tumbler disk and bolt having interengageable means whereby the tumbler disk must be set at another predetermined position to enable the bolt to be released.

9. In a device of the character described, 100 the combination with a pair of members movable to and from each other, of a spindle journaled through each member, a tumbler disk secured to the inner end of each spindle, and an element carried by each 105 member and engageable with the opposite tumbler disk, the respective tumbler disks and elements having interengageable means whereby each tumbler disk must be set at a predetermined position to enable the respective element to be released.

10. In a device of the character described, the combination with a pair of members movable to and from each other, of a spindle journaled through each member, a tumbler disk secured to the inner end of each spindle, a lock bolt slidably carried by one member, and an apertured element carried by the other member and through which the bolt is projectable when the bolt is moved 115 into engagement with the tumbler disks, one end of the bolt and the tumbler disks having interengageable means whereby each of the tumbler disks must be set at a predetermined position to enable the bolt to be released.

11. In a device of the character described, 125 the combination with a pair of members movable to and from each other, of a spindle journaled through each member, a tumbler disk secured to the inner end of each 130

spindle, an element carried by each member and engageable with the opposite tumbler disk, the tumbler disks and respective elements having interengageable means where-
5 by each tumbler disk must be set at a pre-
determined position to enable the respective
element to be released, a sliding bolt carried
by one member and an apertured element
carried by the other member through which
10 one end of the bolt is movable when the same
is projected into engagement with the tum-
bler disks, said end of the bolt and the

tumbler disks having interengageable means
whereby each of the tumbler disks must be
set at a predetermined position to enable the 15
bolt to be retracted.

In testimony that I claim the foregoing as
my own, I have hereto affixed my signature
in the presence of two witnesses.

JACOB HENDRICKSON.
